UNITED STATES PATENT OFFICE

132,113

DESIGN FOR A BROOM

Louis F. Clements, Denver, Colo., assignor of one-half to John B. Furstenberg and Lucie J. Furstenberg, both of Denver, Colo.

Application December 27, 1941, Serial No. 104,879

Term of patent 14 years

To all whom it may concern:

Be it known that I, Louis F. Clements, a citizen of the United States, residing in the city and county of Denver and State of Colorado, have invented a new, original, and ornamental Design for a Broom, of which the following is a specification, reference being had to the accompanying drawing, forming part thereof.

The dominant features of my design are shown in solid lines on the drawing.

In the drawing:

Figure 1 is a front elevation of a broom showing my new design;

Figure 2 is a side elevation thereof; and

Figure 3 is a cross section taken on line 3—3 of Figure 1.

I claim:

The ornamental design for a broom, substantially as shown and described.

LOUIS F. CLEMENTS.
